UNITED STATES PATENT OFFICE.

HENRY L. BAILEY, OF BROOKLYN, ASSIGNOR TO THE TIME TELEGRAPH COMPANY, OF NEW YORK, N. Y.

ELECTRIC CIRCUIT AND APPARATUS FOR SYNCHRONIZING CLOCK-PENDULUMS.

SPECIFICATION forming part of Letters Patent No. 278,846, dated June 5, 1883.

Application filed February 2, 1883. (No model.)

To all whom it may concern:

Be it known that I, HENRY L. BAILEY, a citizen of the United States, and a resident of Brooklyn, in the county of Kings and State 5 of New York, have invented certain new and useful Improvements in Electric Circuits and Apparatus for Synchronizing Clock-Pendulums, of which the following is a specification.

The object of my invention is to provide 10 means for maintaining the movements of a series of automatically-actuated clock-pendulums in unison with the beats of a central standard clock or regulator.

The invention consists in applying to the 15 pendulum of a regulator a circuit-controlling device adapted to periodically and momentarily interrupt the circuit of a battery whose connections are at other times completed through an electric conductor leading to each of the series of secondary pendulums, and in applying 20 to each of the secondary pendulums a device arranged to modify its movements when either faster or slower than the regulator-pendulum, but not to act upon the same when moving in 25 unison therewith. The devices applied to the secondary pendulums comprise an electro-magnet placed near the lower extremity of the pendulum and included in a loop circuit of the main line. The connections of this circuit are automatically so controlled by the movements of 30 the pendulum, to which the electro-magnet is applied, that they are normally completed only during the time or a portion of the time that the main-line connections are interrupted 35 by the regulator-pendulum. It results, therefore, that the electro-magnets are not vitalized so long as the pendulums are in unison. If, however, any one of the secondary pendulums become faster or slower than the regulator, 40 the corresponding branch circuit will be completed during a portion of the period that the main-line circuit remains uninterrupted by the regulator-pendulum, and the electro-magnet included therein will act upon the pendulum, either to accelerate or retard its movement, as may be necessary for the purpose of 45 synchronizing it.

The invention also consists in applying to the coils of the electro-magnets a non-inductive shunt-circuit, automatically brought into 50 action when the electro-magnets are vitalized,

and serving to neutralize the induced currents incident to the discharge of the electro-magnets by the interruption of the circuit there-through.

The accompanying drawing is a diagram illustrating an arrangement of apparatus and circuits embodying my invention as applied to a primary or regulating pendulum and three secondary pendulums, located at different stations, and respectively designated as stations "A," "B," "B²," and "B³."

The regulating-pendulums *a*, *b*, *b²*, and *b³* at the respective stations A, B¹, B², and B³ may be considered as actuated by a suitable 65 mechanical or electrical device of well-known construction, and to have, as nearly as practicable, the same periods of oscillation. The regulating-pendulum *a* is provided with a circuit-breaking device, *C*, which consists of a 70 flexible conducting-spring, *c*, supported at one extremity in a frame, *c'*. The free extremity of this spring carries a contact-point, *t*, which normally rests, by virtue of the resilience of the spring, against a corresponding insulated contact-point, *t'*, carried upon the frame *c'*. The whole device is adjustably supported from a 75 fixed arm, *c''*, by means of an adjusting-screw *c'''*.

Upon the pendulum *a* is mounted a stud or arm, *c⁴*, preferably of non-conducting material, which arm is caused by the swing of the pendulum to impinge against the spring *c* when the pendulum is near the limit of its movement in that direction, thereby causing the contact-point *t* to be separated from the contact-point *t'*.

The contact-point *t'* is electrically connected by means of a conductor, *l*, with one pole of a battery, *E*. The contact-spring *c* is in electrical connection through a main line, *L*, extending through the series of sub-stations B¹, B², and B³ with the remaining pole of the battery *E*. It is evident thus that by properly adjusting the position of the circuit-breaker *C* relative to the pendulum *a* the circuit of the battery *E* may be interrupted during a greater or less portion of the beat of the pendulum.

To each of the pendulums *b*, *b²*, and *b³* at the sub-stations B¹, B², and B³ is applied an 90 electro-magnet, as shown at M¹, M², and M³. These electro-magnets are respectively in-

cluded in loop-circuits of the main line. The connections of these loop-circuits are controlled by circuit-closing devices D' , D^2 , and D^3 , respectively applied to the pendulums b' , b^2 , 5 and b^3 .

The construction and organization of the apparatus at each of the secondary stations are the same, and will therefore be described with reference to the station B' only.

10 The circuit-controlling device D' , which normally acts to complete the circuit-connections of the branch circuit through the electro-magnet M' during a portion of the time the circuit of the battery E is interrupted by the circuit-breaker C , comprises an adjustable frame, d' , supported in a manner similar to the frame c' by an upright, d^2 , and screw d^3 . A flexible contact-spring, d , is rigidly attached at one extremity to the frame d' . The opposite extremity of the spring carries a contact-point, u , which normally rests, by virtue of the resiliency of the spring, against an insulated contact-point, u' , carried in the frame d' . The main-line section l , proceeding from the central station A , is connected with the contact-point u' , and the contact-spring d is likewise connected with the section l' of the main line, proceeding to the next station, B^2 . A second contact-spring, d^4 , is supported in the frame d' in proximity to the spring d , and preferably parallel therewith and insulated therefrom. The free extremity of this spring normally rests against an insulated resting-contact, v , on the frame d' , out of contact with the spring d . The spring d^4 is electrically connected by a conductor, 4, with one terminal of the helix of the electro-magnet M' . The remaining terminal of this helix is connected by a conductor, 3, at a point, 2, with the section l of the main line L .

Upon the pendulum b' is carried a stud or arm, v^3 , arranged to press the contact-spring d^4 out of contact with its resting-contact v , and to cause a contact-point, v' , carried thereon, to 45 strike against a second contact-point, v^2 , carried upon the contact-spring d , thereby closing the circuit of the main line through the conductor 3, electro-magnet M' , and conductor 4, to the spring d^4 , and thence through the spring d to the main-line section l' . Immediately upon the closing of this circuit the further swing of the pendulum causes the spring d to be pressed away from the contact-point u' , thereby interrupting the circuit between the main-line sections l and l' . The connections of the main line at the station will therefore remain closed only through the electro-magnet M' until the pendulum has passed upon its return-beat the point at which the main-line circuit was interrupted.

Attached to the lower extremity of the pendulum b' is a soft-iron armature, m' , which is carried by the vibration of the pendulum through the potential field of force of the electro-magnet M' . The proximity of the electro-magnet, and thus the degree of attraction it will be caused to exert upon the armature m' ,

is rendered adjustable by means of a suitable adjusting-screw, m^2 . The electro-magnet M' is, moreover, preferably so placed with reference to its armature m' and the pendulum that the center of its magnetic field will be at a point between the central point of the vibration of the pendulum and one extreme of its swing. This position may, if desired, be rendered adjustable by supporting the standard k , which carries the vertical adjusting-screw m^2 , in a rack, k' , in which it is longitudinally adjustable by means of a thumb-screw, k^2 . The rack k' is preferably formed in the arc of a circle whose center coincides with the point of suspension of the pendulum.

The position of the circuit-controlling device D' relative to the circuit-breaker C is such that normally the circuit will be interrupted at the points t and t' immediately before the circuit is closed through the electro-magnet M' . So long, therefore, as the pendulums are beating in unison the circuit of the battery E will not be closed through any of the electro-magnets. If, on the other hand, one of the pendulums, as b^2 , is faster than the regulating-pendulum a , the circuit through the corresponding electro-magnet, M^2 , will be closed at the points v' and v^2 of the circuit-controller D^2 before the connections of the battery E have been interrupted at the points t and t' . The electro-magnet M^2 will therefore be vitalized and remain so until the circuit is broken either by the circuit-closer C or the controller D^2 . Likewise, if one of the secondary pendulums, as b^3 , be slower than the regulating-pendulum a , the corresponding electro-magnet, M^3 , will be vitalized during the time that the circuit therethrough remains closed at the points v' and v^3 of the circuit-controller D^3 after the completion of the circuit of the battery E at the points t and t' .

For the purpose of adapting the electro-magnets M to most advantageously retard a fast pendulum and accelerate a slow one, I prefer to so adjust their positions relative to the arcs of the vibrations that the centers of the field of force of each shall be intermediate between its central point of vibration and one extremity, o , thereof, and the point selected is preferably also intermediate between the central point of the arc and the point which the pendulum reaches when the branch circuit of the corresponding electro-magnet is closed by its circuit-controller D . The relative positions in the arc which I prefer are approximately indicated in the drawings as follows: p is the central point in the swing of the pendulum—that is to say, its point of stable equilibrium; o , the extreme limit of its movement toward the circuit-controlling device; s , the point at which the pendulum has arrived when the main-line circuit is interrupted by the circuit-breaker C , and s' the position of the pendulum at the instant the circuit-controller D acts to close the loop-circuit. The center of the field of force of the electro-magnet M is at n . It will be evident, thus, that if the pendulum b^2

is moving in the direction indicated by the arrow x' , and slightly in advance of the pendulum a , the electro-magnet M^2 will be vitalized when that pendulum has reached the 5 point s' , thereby acting to retard the pendulum. Before the pendulum b^2 has completed its movement in the direction indicated by the arrow x' the circuit of the battery E will have been interrupted by the circuit-breaker C , and the 10 electro-magnet will therefore no longer be vitalized. If, on the other hand, one of the pendulums, as b^2 , be a very little slower than the regulator-pendulum a , the circuit of the battery E being first interrupted by the circuit-breaker C , the electro-magnet M^2 will not be vitalized until both pendulums are moving in the direction indicated by the arrows $y' y'$, and the pendulum a has arrived at the point s , thereby allowing the main-line circuit to be 15 closed by the circuit-breaker C . The electro-magnet M^2 will therefore remain vitalized until the circuit therethrough is interrupted by the circuit-controller D^2 . An attraction will therefore be exerted upon the armature m^2 20 until it reaches the point s' , thereby tending to hasten the descent of the pendulum and to cause it to gain upon the pendulum a . If a single impulse proves insufficient to bring the pendulums into unison, the operation will be 25 repeated at every beat until the desired result is accomplished.

In each of the instances thus far considered it has been assumed that the secondary pendulum is very nearly in unison. If, however, 30 for any reason, one of the secondary pendulums were so far out of unison that the main-line circuits were closed during the entire time the contact-points v' and v^2 are in contact, the corresponding electro-magnet, M , will be vitalized, 35 and attract its armature equally during its movements from and toward the point s' . The effect upon the pendulum of these forces, considered without reference to attendant forces, will be to accelerate and to retard the pendulum 40 equally. If, however, the attendant effects were such as to cause the one force to exceed the other, the pendulum will ultimately be brought into unison with the regulating-pendulum in the manner already described.

For the purpose of counterbalancing the resistance offered by the electro-magnets M , an adjustable artificial resistance, R , is preferably included at each sub-station in the section l of the main line connecting the preceding station therewith, at a point between the contact-point u' and the point 2 , at which the conductor 50 3 is attached.

In the practical operation of the device it is desirable that the discharge of the electro-magnet M , after their circuits have been 55 interrupted, should be as nearly as possible instantaneous, and also that the induced currents therefrom should be neutralized for the purpose of preventing the occurrence of disruptive discharges at the points v' and v^2 . To effect these results, I construct the electro-magnet M with two coils and cores in the usual

manner, and apply thereto a device operating to close a shunt-circuit around the coils of the electro-magnet during a portion of the time 60 the magnet is vitalized. This shunt-circuit remains closed a sufficient time after the circuit through the electro-magnet is interrupted to allow the discharge to occur. This device, which is illustrated in connection with the 65 electro-magnet M' , consists of an armature, n' , carried upon an armature-lever, n^2 , above the pole n^3 of the magnet M , and so constructed that when attracted into proximity thereto it will make contact with an adjustable contact-spring, n^4 . The lever n^2 is normally held away from the pole n^3 and the contact-spring n^4 by means of a suitable retractile spring, n^5 . The contact-spring n^4 is electrically connected by a conductor, 5 , with the conductor 3 , leading from 70 one terminal of the coils of the combined electro-magnet, and the armature n' is likewise connected through a conductor, 6 , and a suitable adjustable non-inductive resistance, r , with the conductor 4 leading from the other terminal of 75 the coils of the electro-magnet. The spring n^4 is so adjusted that the armature n' will be brought into contact therewith at an intermediate point in its vibration, thereby closing the shunt-circuit. The spring yields to the 80 pressure of the armature and is deflected toward the pole of the magnet, still maintaining the shunt-circuit closed. When the circuit through the electro-magnet is interrupted the shunt-circuit will remain closed until the 85 spring-contact has returned to its normal position. This will allow a sufficient time for the discharge of the magnet to be completed through the shunt-circuit, and no effect therefore will be manifested at the points v' and v^2 . 90 The path offered to the induced current through the shunt-circuit serves also to hasten the discharge of the electro-magnet, thus preventing it from acting upon its armature m after its circuit has been interrupted. When this 95 shunt-circuit is employed the resistance offered by the artificial resistance r is preferably made approximately equal to the total resistance of the coils of the electro-magnet, and the resistance R is preferably made approximately one-half as great as the resistance r —that is, equal to the resultant resistance offered by the two 100 circuits 3 and 5 .

I have illustrated the above-described device as applied to one pendulum only; but I 105 contemplate applying it to any or all of the pendulums in a system.

It is evident that any required number of electro-magnets included in a single circuit 110 3 may be shunted in this manner by the action 115 of a single circuit-closing device, such as that described.

I do not herein claim the specific construction of the devices for controlling the connections of the shunt-circuit around the coils of the electro-magnets, as I propose to embody 120 the same in an application to be hereafter filed by me.

I claim as my invention—

1. The combination, substantially as hereinbefore set forth, with a battery and a main line constituting the circuit of said battery, of a regulator-pendulum, a circuit-breaker actuated by said pendulum for momentarily interrupting the circuit-connections of said main line, a series of automatically-actuated pendulums, a series of electro-magnets, one for each of said pendulums, and an independent circuit-closer applied to each of said automatically-actuated pendulums, each of which circuit-closers is adapted to place the corresponding electro-magnet in the circuit of said main line normally during a portion only of the time the circuit of said battery is interrupted. 15
2. The combination, substantially as hereinbefore set forth, with a main line and a battery applied thereto, of a regulator-pendulum, a circuit-breaker acting to interrupt the connections of said battery during a portion of the beat of said pendulum, a series of automatically-actuated pendulums, a series of electro-magnets, respectively applied to said automatically-actuated pendulums, and means, substantially such as described, for causing each of said electro-magnets to be included in the circuit of the main line during periods of time dependent upon the phase of the corresponding pendulum relative to that of the regulator-pendulum. 25
3. The combination, substantially as hereinbefore set forth, of a main line, means, substantially such as described, for periodically interrupting an electric current normally traversing the same, a series of vibrating pendulums, a series of electro-magnets respectively applied to a series of armatures carried upon said pendulums, and an independent circuit-closer applied to each of said vibrating pendulums, each of which circuit-closers is adapted to place the corresponding electro-magnet to be periodically included in the circuit of the main line during a period of less duration than the periods during which the circuit of the main line is interrupted. 35
4. The combination, substantially as hereinbefore set forth, of a standard or regulator pendulum, an automatically-actuated pendulum, an armature carried at the extremity of said automatically-actuated pendulum, an electro-magnet located in proximity to the arc of oscillation of said armature at a point between one extremity and the center of the same, and means, substantially such as described, acting to cause said electro-magnet to be periodically vitalized only when said automatically-actuated pendulum is not beating in unison with said regulator-pendulum. 55
5. The combination, substantially as hereinbefore set forth, of a pendulum, an armature carried at the extremity of said pendulum, an electro-magnet located in proximity to the arc of oscillation of said armature at a point be-
- tween one extremity and the center of the same, a main line and a circuit-closer operated by the movements of said pendulum and acting to include said electro-magnet in the circuit of said main line after said armature has been carried beyond the central point in the field of force of said electro-magnet by the spring of said pendulum away from the central point of its oscillation, and to cut said electro-magnet out of circuit before said armature is returned to said central point in its field of force. 65
6. The combination, substantially as hereinbefore set forth, of a vibrating pendulum, an armature carried at the extremity thereof, an electro-magnet situated in proximity to its arc of vibration, a main line, a main battery the connections of which are normally completed through said main line independently of said electro-magnet, a circuit-breaker adapted to periodically interrupt the connections of said battery with said main line, and a circuit-closer applied to said vibrating pendulum and adapted to substitute for the normal connections of said main line a circuit through the coils of said electro-magnet. 75
7. The combination, substantially as hereinbefore set forth, of a vibrating pendulum, an armature carried upon the extremity of said pendulum, an electro-magnet situated in proximity to its arc of vibration, a main line, a conductor composing a section of said main line, an artificial resistance included in the circuit of said section approximately equal to the resistance of said electro-magnet, and means, substantially such as described, for substituting for said section of the main line a conductor including said electro-magnet. 80
8. The combination, substantially as hereinbefore set forth, of a vibrating pendulum, an armature carried upon the extremity of said pendulum, an electro-magnet situated in proximity to its arc of vibration, a main line, a conductor composing a section of said main line, an artificial resistance included in the circuit of said section approximately equal to the resistance of said electro-magnet, means, substantially such as described, for substituting for said section of the main line a conductor including said electro-magnet, and a vibrating armature applied to said electro-magnet acting to close a shunt-circuit around the coils of the same while in proximity to the poles thereof. 90
- In testimony whereof I have hereunto subscribed my name this 1st day of February, A. D. 1883.
